CATALYTIC CONVERSION OF HYDRO-CARBONS

Charles L. Thomas and Herman S. Bloch, Chicago,
Ill., assignors to Universal Oil Products Company,
Chicago, Ill., a corporation of Delaware

Application August 21, 1939, Serial No. 291,196

3 Claims. (Cl. 196—10)

This invention relates to a process for converting hydrocarbon oils into substantially saturated motor fuels. More particularly, the process relates to the catalytic conversion of hydrocarbon oils of higher than gasoline boiling range. Although the source of hydrocarbon converted according to the present process is usually crude petroleum oil, similar oils from other suitable sources such as shale oil, coal tar, etc., may also be used.

The motor fuels produced according to the present invention may be used in any internal combustion engine, but they are particularly suitable for use in airplane motors because of the good antiknock properties, particularly in regard to improvement in octane number upon the addition of tetraethyl lead, and because they are substantially olefin free and meet the strict specifications applied to this type of fuel by the aviation industry.

A number of processes have been developed to increase the yields of gasoline obtainable from petroleum oils among which is the non-catalytic cracking process, wherein oils of greater than gasoline boiling range are subjected to decomposition under suitable conditions of temperature and pressure to convert them to substantial yields of gasoline. In a similar fashion, naphthas and gasolines produced by the straight-run distillation of petroleum oils may be reformed to improve their octane numbers and thus their value as motor fuel. Those reactions are carried out in various non-catalytic cracking operations.

More recently processes have been developed wherein hydrocarbon oils are contacted with suitable catalytic masses and converted into increased yields of motor fuels having better antiknock properties than are usually economically obtainable by the non-catalytic thermal process. Various other types of processes including polymerization of olefins, alkylation of paraffins or aromatics with olefins, etc., have been developed for use in conjunction with these methods to improve the properties of the finished gasoline and increase the yields of motor fuel obtainable.

It is with improvements in such methods of catalytically converting hydrocarbon oils into premium grade motor fuels that the present invention is concerned.

In one specific embodiment, the present invention comprises mixing hydrocarbon oil with an olefin-containing gasoline produced in a catalytic cracking step as hereinafter described,

5 contacting the mixture with a cracking catalyst in a primary conversion step at a temperature within the range of approximately 600—900° F. under a pressure of substantially atmospheric to 1000 pounds per square inch, separating the gasoline and gas, passing the insufficiently converted oil with or without the addition of a portion of the raw oil charge to a secondary catalytic cracking step wherein it is contacted with a cracking catalyst at a temperature within the 10 range of 800—1200° F. and a pressure of substantially atmospheric to 100 pounds per square inch, passing the reaction products to a fractionation step, recycling a portion of the insufficiently converted oil to the secondary catalytic cracking step, recovering olefin containing gasoline which is mixed with the original oil charge as 15 previously described, passing the gases containing olefins to a polymerization step wherein the olefins are subjected to the action of a catalyst 20 under conditions of temperature and pressure adequate to convert them into substantially gasoline boiling range material, passing the polymer product in combination with the original oil charge and the high temperature catalytic gasoline to said primary conversion step. 25

The catalysts which are useful in the present process may include cracking catalysts of various types, such as synthetic precipitated composites consisting essentially of a major portion of precipitated silica having added thereto relatively minor portions of precipitated refractory oxides to form masses consisting of silica-alumina, silica-zirconia, silica-alumina-zirconia, etc., 30 said composites being substantially free of alkali-metal compounds.

In the following specification, the terms "silica-alumina, silica-zirconia, and silica-alumina-zirconia" masses are used in a broad sense. Inasmuch as the chemical knowledge of the solid state has not been developed perfectly, it is not possible to give the structure of all solid substances. All that can be said definitely concerning these masses is that they contain silicon, oxygen, aluminum, and/or zirconium in combination. Generally speaking, however, all these components indicate more or less low catalytic activity individually but in the aggregate display high activity. This activity is not an additive function, it being relatively constant for a wide range of proportions of the components, whether in molecular or fractions of molecular proportions. No one component can be determined as the one for which the remaining components 55 may be considered as the promoters according

to conventional terminology, nor can any components be determined as the support and the others the catalyst proper.

According to the description of the preparation of the preferred catalyst given hereinafter, precipitated hydrated alumina and/or hydrated zirconia are composited with precipitated hydrated silica gel, otherwise known as silica hydrogel, and then the composite is washed, dried and calcined, producing a catalytic mass. However, the different catalysts which may be so produced therefrom do not necessarily give exactly equivalent results.

The higher temperature catalytic cracking step may be carried out within the range of approximately 800°-1200° F., a pressure of substantially atmospheric or slightly superatmospheric, say of the order of 50-200 pounds per square inch, using any suitable cracking catalyst such as acid-treated clays, and preferably catalysts of the type described in a general way as silica-alumina, silica-zirconia, and silica-alumina-zirconia catalysts. The operating conditions under which the olefin containing gas-line from the high temperature step is converted is within the range of approximately 600°-900° F., and under pressures of substantially atmospheric to 1000 pounds per square inch.

The catalytic masses employed in both conversion steps undergo an accumulation of carbonaceous deposits which must be removed from time to time, and this is suitably done by heating in the presence of oxygen-containing gas at a temperature of 1000° F. or higher.

The catalyst employed in the polymerization step may be the so-called solid phosphoric acid catalyst which is prepared by mixing liquid phosphoric acid with kieselguhr or similar suitable siliceous material, forming into shapes, drying and calcining. The catalyst is employed at temperatures of approximately 275°-400° F. and pressures of approximately 200-1000 pounds per square inch.

Another catalyst which may be used is sulfuric acid of greater than 60% concentration. The conversion is carried out at a temperature of approximately 80-250° F. and a pressure of the order of 200 pounds per square inch.

One embodiment of the present invention is illustrated in the accompanying drawing, which is diagrammatic and should not be interpreted as limiting the invention to the exact apparatus or conditions shown. The drawing has not been made to scale, nor has any attempt been made to proportion the equipment exactly.

Referring to the drawing, the raw oil charge enters through line 1, valve 2, valve 3, line 4, valve 5, pump 6, valve 7 and coil 8 which is disposed in heater 9. The oil is mixed with catalytic cracked gasoline from a step to be described later, which enters from line 10 and valve 11, joining with line 4. The hydrocarbon mixture leaves the coil at a temperature of approximately 500-900° F. and a pressure of substantially atmospheric to 1000 lbs./sq. in. through line 12 and valve 13, entering catalytic reactor 14. The reaction products are removed through line 15, valve 16, to fractionator 17, from which gas and gasoline are removed through line 18 and valve 19 to storage through suitable stabilizers, heat exchangers, condensers, etc., not shown in the interest of simplifying the drawing. Insufficiently converted oil is removed through line 20. A portion of the oil may be withdrawn from the system through line 21 and valve 22. Normally

all of the oil is passed through line 23, valve 24, line 25, valve 26, pump 27, valve 28 to coil 29, which is disposed in heater 30. If so desired, a portion of the raw oil charge may be mixed with the insufficiently converted oil by passing through line 1, line 31, valve 32, and line 25. The oil is heated in the coil to a temperature of approximately 800°-1200° F. and a pressure of substantially atmospheric to 1000 pounds per square inch. It leaves the coil through line 33 and valve 34 to catalytic reactor 35. The reaction products pass through line 36 and valve 37 to fractionator 38, which may suitably consist of a separate fractionator and stabilizer, but is shown as one vessel in the interest of simplifying the drawing. Catalytically cracked gasoline is removed through line 10 and valve 11, being mixed with the raw oil charge in line 4 and thence treated as described above. A portion of the cracked gasoline may be withdrawn through line 39 and valve 40. A part of the insufficiently converted oil may be removed from the system through line 41 and valve 42, and a part may be recirculated through line 43 and valve 44, which combines with line 25 and passes thence to the higher temperature catalytic cracking step. The gaseous hydrocarbons are removed through line 45, valve 46, pump 47, valve 48 to polymerizer 49, wherein the olefins are converted to substantially gasoline boiling range material. The polymerized products are removed through line 50 and valve 51 to stabilizer 52, from which the residual gases are removed from line 53 and valve 54. Although a fraction of the polymer may be separately withdrawn through line 55 and valve 56, according to the preferred operation the liquid polymer is withdrawn through line 57 and valve 58, combining with the raw oil charge in line 1, and thence to line 4, through which it passes as previously described to the low temperature catalytic conversion step.

Substantially improved yields of high anti-knock, olefin-free motor fuel which is stable in storage, low in sulfur content, and has a high degree of susceptibility to added tetraethyl lead are produced in the manner described. This is illustrated by the following example which should not be interpreted as limiting the invention to the exact conditions employed.

A Pennsylvania gas oil of 37.0° A. P. I. gravity was processed as described in the above specification the low temperature conversion step being carried out at a temperature of 750° F. and a pressure of 100 pounds per square inch. Mixed with this oil was the catalytically cracked gasoline from the higher temperature conversion step which was operated at 930° F. The charge from which the catalytically cracked gasoline was produced comprised the insufficiently converted oil from the lower temperature step. The gases from the higher temperature step were polymerized in the presence of solid phosphoric acid catalyst at a temperature of 410° F. and a pressure of 400 pounds per square inch. The polymer was mixed with the raw oil charge and passed to the low temperature conversion step. The catalyst employed in both high and low temperature conversion steps was a substantially sodium-free silica-alumina-zirconia mass. The substantially olefin-free gasoline of 400° F. end point was recovered from the low temperature step. It had an octane number of 79, which was increased to 95 by the addition thereto of 6 cc. of tetraethyl lead per gallon. The total yield of gasoline amounted to 81% of the raw oil charge. The

gasoline had a bromine number of 1, an oxygen bomb induction period in excess of 24 hours, 1 milligram of copper-dish gum per 100 cc., and a sulfur content of less than 0.01%.

We claim as our invention:

1. A process for producing substantially saturated gasoline of high anti-knock value which comprises combining olefinic gasoline with hydrocarbon oil heavier than gasoline, subjecting the resultant mixture to the action of a cracking catalyst at a temperature of about 600-900° F., whereby to produce gasoline of low olefin content, separating the low olefin content gasoline from conversion products heavier than gasoline, catalytically cracking at least a portion of said heavier products at higher temperature than is maintained in the first-mentioned conversion step, thereby forming olefinic gasoline, supplying the latter to the first-mentioned conversion step as at least a portion of the olefinic gasoline which is combined with said hydrocarbon oil, subjecting olefinic gas formed by the higher temperature catalytic conversion to polymerization and supplying resultant polymers to the first-mentioned conversion step.

2. The process as defined in claim 1 further characterized in that said heavier products are cracked at a temperature of about 800-1200° F.

3. A process for producing substantially saturated gasoline of high anti-knock value which comprises combining olefinic gasoline with hydrocarbon oil heavier than gasoline, subjecting the resultant mixture to the action of a cracking catalyst at a temperature of about 600-900° F., whereby to produce gasoline of low olefin content, separating the low olefin content gasoline from conversion products heavier than gasoline, cracking at least a portion of said heavier products at higher temperature than is maintained in the first-mentioned conversion step, thereby forming olefinic gas and gasoline, subjecting olefinic gases thus formed to polymerization and supplying resultant olefin polymers to the first-mentioned conversion step as at least a portion of the olefinic gasoline which is combined with said hydrocarbon oil.
